THREAD CUTTING AND SECURING MEANS

Perham F. Hurst, deceased, late of Seattle, Wash.,
by Anna Beulah Hurst, administratrix, Seattle,
Wash.

Application February 3, 1932. Serial No. 590,759

1 Claim. (Cl. 30—14)

This invention relates to an improved thread cutter and securing means involving a combined holder and cutter, for use on a spool of thread. The primary object of the invention is the provision of a device of this character which is comparatively inexpensive in cost of manufacture; which may with facility be attached to and used with a spool of thread, and which may with equal facility be withdrawn from or detached from the spool, when the latter is emptied of its thread, and the device may thereafter be attached to another spool of thread. In carrying out the invention there is employed a holder of resilient metal, which is provided with a cutting edge for the thread, and utilize means for attaching the holder to the spool, and for holding the end of the thread in such manner that it may readily be cut when a length of thread is desired, and the remaining end of the thread is retained in position where it is readily accessible for a succeeding length to be cut therefrom.

The invention consists in certain novel combinations and arrangements of parts as will hereinafter be more fully set forth and claimed. In the accompanying drawing there is illustrated one complete example, and a modification thereof, of the physical embodiment of the invention wherein the parts are combined and arranged according to the best mode thus far devised for the practical application of the principles of this invention.

Figure 1 is a side view of a spool of thread having one of the devices of my invention attached thereto.

Figure 2 is an end view as seen from the right in Figure 1.

Figure 3 is a longitudinal sectional view through one end of the spool, as at line 3—3 of Figure 2.

Figure 4 is a transverse sectional view at line 4—4 of Figure 3.

Figure 5 is a view at one end of the spool of thread showing the holder in section, as at line 5—5 of Figure 2.

Figure 6 is an end view of a spool of thread with a modified form of my invention attached thereto.

Figure 7 is a longitudinal sectional view at one end of the spool, at line 7—7 of Figure 6.

Figure 8 is a view at one end of the spool of thread, showing the cutter-holder in section as at line 8—8 of Figure 6.

In the drawing there is illustrated a conventional spool of thread as S with the thread T

wound thereon in usual manner, and the spool is fashioned with the usual heads or flanges 1, 1. The combined thread holder and cutter comprises an attaching plate 2 formed with an opening 3 therein, and adapted to lie flat against the end face of one of the heads of the spool. The attaching plate is secured in position against the head of the spool by means of a tack 4 which is fashioned with a large round head 5, and the tack of course is driven through the hole 3 and into the wood of the spool for fastening the device to the spool.

The attaching plate is preferably fashioned of resilient metal and has an integral, arcuate flange 6 disposed at right angles to the attaching plate, 70 and this flange, which conforms to the contour of the periphery of the circular head or flange of the spool, is of slightly greater diameter in its curvature, than the spool-head, to permit the thread T to be slipped between the flange and the spool, and there be held by friction. The flange 6 thus forms an anchoring cleat for the end of the thread, and to facilitate the entrance of the thread to the space beneath the cleat, the flange, at its opposite ends, is provided with upturned 80 guides 7 and 8, beneath which the thread is caught for anchoring purposes.

As best seen in Figures 2 and 5, the attaching plate is provided with a cutting edge 9, which is formed by grinding down a portion of an edge of the plate, and this cutting edge is located adjacent the junction of the attaching plate with the anchoring cleat.

In Figure 1 the end of the thread T is shown as caught and retained, under the holder or anchoring cleat, where it is readily accessible when a length of thread is desired from the spool of thread. In Figure 5 a length of thread is illustrated in position to be severed from the spool of thread, and it will be noted that the thread is passed under the anchoring cleat, around the attaching plate, and across the cutting edge, so that a pull on the length of thread will sever it on the cutting edge. After the length of thread has been severed, the remaining end of the spool-thread, as indicated by dotted lines, projects into position where it is readily accessible for a succeeding length of thread.

In some instances, it is not desirable to pass the thread around the attaching plate, as in Figure 5, and therefore there is devised and illustrated a modified form of the combined holder and cutter.

In Figures 6, 7, and 8, where the modification is illustrated, the attaching plate 10 is fash-

ioned with a triangular or sharpened spur or stud 11, perpendicular to the plate, and driven into the wood head of the spool, and the cutting edge 12 is fashioned at the left edge of the plate, 5 instead of at the right edge as in Figure 2.

As seen in Figure 8, the thread is passed beneath the anchoring cleat 6, where it is held by friction, and after the desired length has been pulled from the spool, through the holder, the 10 length of thread is severed by turning the length back and giving it a jerk against the cutting edge 12, leaving a short end of the thread beneath the anchoring cleat for further use.

The end of the spool-thread is thus, at all times, held beneath the anchoring clip or flange 6 to 15 prevent displacement and unwinding of the thread from the spool, and the extremity of the thread is accessible when it is desired to unwind a length from the spool.

20 The combined holder and cutter is capable of use in various ways, and the threads or thread-ends may be manipulated for engagement with

the anchoring cleat by either a right-hand person or a left-hand person, as it will be apparent that the thread may enter the holder beneath either of the guides 7 or 8.

Having thus fully described the invention, what 80 is claimed as new and desired to be secured by Letters Patent is:—

The combination with an attaching plate, and 85 means for fastening said plate to a spool, of an integral, arcuate flange on said plate conforming to the rounded contour of the spool, said flange having oppositely projecting upturned ends and forming an anchoring cleat, and a cutting edge 90 fashioned on the plate adjacent the junction of the flange with the plate whereby a portion of the spool-thread may be looped around the plate and under the upturned ends, and a length of thread severed from the spool-thread, leaving a loose-end on the spool thread.
